UNITED STATES PATENT OFFICE

2,313,684

KNITTING ACCESSORY

Ivar V. Thulin, Upper Darby, Pa.

Application August 21, 1941, Serial No. 407,702

6 Claims. (Cl. 242—149)

My invention relates to a new and useful knitting accessory and particularly to improvements concerning the structure disclosed in my United States Patent No. 2,172,074, dated September 5, 1939.

The device is especially adapted for use in connection with knitting but also can be used in crocheting and similar work. The device becomes, in effect, a third hand and properly directs the material strand to needles held in the operator's hands by a simple rotary motion imparted by the index finger. Such a device eliminated the most difficult part of knitting by providing the proper tension on the yarn or other material strand at all times, without depending upon the touch of the operator, thereby producing speed, efficiency and practically perfection in knitting because each stitch will be even, smooth and perfectly formed.

One of the objects of the present invention is to simplify the construction of the accessory by using few parts, thus causing a saving in material, labor, time and expense.

Another object of this invention is to provide a construction that simplifies the threading operations.

A further object of the invention is to provide a knitting accessory including a split bendable ring for placement upon a person's finger and an arm projecting from said ring having its outer end constructed to constitute a feed loop or eye with an entrance leading thereto and having a tongue acting as a closure for and a guide to said entrance.

A still further object of this invention is to provide a knitting accessory consisting of two units assembled into a unitary structure, one unit comprising the ring with its arm having the feed loop or eye and the other unit including a tension clip and guide chock fixed to and cooperating with said first unit.

With the above and other objects in view, this invention consists of certain details of construction and combination of elements hereinafter set forth and then designated by the claims.

In order that those skilled in the art to which this invention appertains may understand how to make and use the same, I will describe its construction and operation by referring by numerals to the accompanying drawing forming a part hereof, in which:

Fig. 1 is a view looking over an operator's shoulder to show how the knitting accessory is used.

Fig. 2 is a plan view of the knitting accessory.

Fig. 3 is a longitudinal sectional view thereof.
Fig. 4 is a section on the line 4—4 of Fig. 2.

Fig. 5 is also a sectional view on the line 5—5 of Fig. 2.

Fig. 6 is an outer end view of the device.

Fig. 7 is a fragmentary plan view of the arm blank.

In carrying out my invention as herein embodied 10 represents a split ring of relatively stiff bendable material to permit expansion or contraction thereof for adjustment to the size of a person's finger. An arm or extension 11 projects from one edge at the top of the ring as an integral part thereof and therefore is of the same bendable material, the purpose of which will be explained hereinafter.

During the blanking operations the outer end of the arm 11 is fashioned as shown in Fig. 7 to provide a horn 12 and a tongue 13, the inner end of which is turned up to produce a flange 14 and provide a smooth or finished border, with a substantially semi-circular or arcuate recess 15 between said horn and tongue, the edge of the arm surrounding said recess being turned down to produce a flange 16 and form a smooth or finished border. The tongue 13 is then bent around so as to overlap the horn and form the feed eye 17 with a lateral entrance covered by the tongue which acts as a guide to said entrance. The tip of the tongue is canted outward to permit easy insertion of the material strand beneath said tongue.

On the ring is mounted the combined tension clip 18 and guide chock 19. This unit is produced from a single piece of flat spring material and fashioned to provide a neck 20, a head 21 offset to one side of the neck and said chock 19 which projects from the same side of the neck as said head but spaced therefrom and located adjacent the inner end of the ring when considered with relation to the accessory in use on a person's finger. Said guide chock has a curved portion which, with the ring, forms an eye 22 for the passage of the material strand and the free end of said guide chock flares outward to form a lip 23 for easy insertion of the material strand into the eye 22.

The head 21 of the tension clip has a longitudinal channel 24 in its under face, preferably formed by bending said head into an inverted V-shape in cross section and in alignment with both eyes 17 and 22. The outer end of the head is slightly turned up to provide a lip 25 and said head is preferably set at an angle to the arm 11 and said lip and angular position of the head permit knots, knobs or other protuberances on

the material strand to readily enter the channel and pass beneath the tension clip from either direction. As the head of said tension clip is free to move to and fro relative to the arm 11 an unobstructed passage at the side of said head is provided which leads to the channel 24 so the material strand may be inserted laterally beneath the tension clip instead of having to be threaded lengthwise.

To thread the accessory, hold the ring in the left hand with the arm extending outward. With the right hand pull the material strand under the tongue 13 until said strand enters the feed eye 17, then carry the strand rearward and insert it laterally under the head of the tension clip and finally said strand is carried back and inserted under the lip 23 of the guide chock 19 and pulled into the guide eye 22 at which time the device is ready for use. To unthread the device or remove it from the material strand, the above operations are reversed.

With the device threaded as above outlined, it is placed upon the index finger of the right hand so that the feed eye 17 will be in proximity to the knitting operations and as a stitch is picked off one needle a portion of the material strand is looped about the pointed end of the picking needle, through a generally rotary motion imparted to the feed eye 17 by the in and out and to and fro movements of said index finger. The particular location and arrangement of the feed eye 17 and because of the smooth border of said eye, the material strand will be laid down properly and without any chance of knots, knobs or other protuberances catching on sharp or angular edges that might prevent movement of the strand, break or otherwise damage the same. Due to the tension clip extending from its anchorage point in the direction of movement of the material strand through the device a smooth but firm pressure is applied to the material strand and such action cannot be obtained with a tension device situated crosswise of the direction of movement of the material strand. The unique formation and disposition of the tension clip permits use of the accessory in connection with knobby and irregular yarns.

Because of the fact that the accessory may be threaded and unthreaded at any time without severing the material strand or passing such strand endwise through encircling means, said accessory may be removed and replaced whenever desired thereby enabling the knitter to transfer the device from one piece of work to another; to temporarily remove it, as when discontinuing operations for some reason; to readily and quickly apply it to other work; and to perform these acts for any other reason.

The device is also adapted for use as a thread tension and guide in connection with the operations of crocheting in which instance the finger supporting the accessory is not especially moved about but is merely retained in a position that will cause the thread to assume a position in proximity to the needle while the latter is in use.

Of course I do not wish to be limited to the exact details of construction herein shown and described as these may be varied within the scope of the appended claims without departing from the spirit of my invention.

Having described my invention, what I claim as new and useful is:

1. A knitting accessory comprising a ring to be slipped on a person's finger, an elongated arm projecting from the outer edge of said ring and extending beyond the end of the person's finger in a plane substantially parallel thereto when in use, said arm having a recess at its outer end, a horn at one side at the outer end of said arm, a tongue at the opposite side at said outer end of said arm, said tongue being curved around and overlapping the horn and spaced therefrom to form a feed eye from the recess and provide a side entrance thereto between the tongue and horn and also act as a gate for said entrance, a guide chock on the ring adjacent its inner edge and open at the side to permit lateral insertion of the material strand thereinto, and a tension clip located between the feed eye and guide chock and anchored on said ring, said clip having an unobstructed passageway thereto at one side to permit lateral insertion of said strand beneath said clip.
2. The structure in claim 1 wherein the material of the border of the recess is turned down.
3. The structure in claim 1 wherein the inner edge of the tongue is turned up.
4. The structure in claim 1 wherein the material of the arm about a portion of the recess is turned down and the material along a portion of the inner edge of the tongue is turned up to provide a smooth border for the feed eye.
5. A knitting accessory including a ring, an arm projecting from the outer edge of said ring, said arm having a feed eye in its outer end, a tension clip comprising a neck having a portion fixed to the ring and projecting towards the arm and a head offset to one side of the neck and overlying the arm, and a guide chock formed integral with the neck of the tension clip in the region of its point of connection to the ring and projecting from the same side of the neck as the head, said guide chock being fashioned to provide a guide eye and the end of said guide chock being free to permit lateral insertion of a material strand beneath the guide chock into the guide eye.
6. A knitting accessory comprising two units joined into a unitary structure, one of said units comprising a split ring, an integral arm projecting from the outer edge of said ring, said arm having a recess at its outer end, a horn at one side of the outer end of said arm, and a tongue at the other side of the outer end of said arm and curved around and overlapping and spaced from the horn to form a feed eye from the recess and provide a side entrance thereto between the tongue and horn and also act as a gate for said entrance, the other unit comprising a neck, an integral head offset to one side of said neck at one end thereof, and an integral guide chock offset to the same side of the neck as the head and at the other end of said neck, said guide chock fashioned to provide a curved portion and a lip, said second unit being fixed in the region of the guide chock to the ring adjacent its inner edge considered with relation to the device in use, the curved portion of the guide chock coacting with the ring to form a guide eye and the head coacting with the arm to constitute a material strand tensioning means.
